(57) **CLAIM**

The ornamental design for a low voltage electrical receptacle, as shown and described.

DESCRIPTION

FIG. 1 is a perspective view of a low voltage electrical receptacle showing our new design;

FIG. 2 is a top plan view thereof;

FIG. 3 is a bottom plan view thereof;

FIG. 4 is a front elevation thereof;

FIG. 5 is a rear elevation thereof;

FIG. 6 is a right side elevation thereof;

FIG. 7 is a left side elevation thereof; and,

FIG. 8 is a perspective view thereof, in a use condition.

In the drawings, the broken lines depict environmental subject matter only and form no part of the claimed design.
